UNITED STATES PATENT OFFICE.

CHARLES C. CLOUSER, OF BELLWOOD, PENNSYLVANIA.

CABINET OAT SPROUTER.

Application filed April 25, 1923. Serial No. 634,522.

To all whom it may concern:

Be it known that I, CHARLES C. CLOUSER, a citizen of the United States, residing at Bellwood, in the county of Blair and State 5 of Pennsylvania, have invented certain new and useful Improvements in a Cabinet Oat Sprouter, of which the following is a specification.

This invention relates to sprouters and 10 more particularly to an improved device for holding a plurality of relatively shallow pans in which oats may be sprouted to provide green food for poultry.

One of the objects of the invention is to 15 provide a cabinet in which may be arranged a plurality of pans to contain sprouting oats and which will be so constructed and arranged as to permit the uppermost pan to be withdrawn from the cabinet while a 20 single movement of the foot of the operator on a lift lever associated with suitable mechanism, will raise the remaining pans to a higher position so that a new pan may be placed in the bottom of the cabinet, thus 25 avoiding the necessity of successively removing the pans from their respective compartments and raising them to a higher compartment as is necessary with the devices now generally in use.

30 Other objects of the invention will appear upon consideration of the following detailed description and accompanying drawings, wherein:

Figure 1 is a front elevation of the cabinet 35 constructed in accordance with my invention.

Figure 2 is a horizontal section taken on the line 2-2 of Figure 1.

Figure 3 is a vertical section taken approximately on the line 3-3 of Figure 2.

Figure 4 is a detailed view of the lifting mechanism shown in extended position.

Figure 5 is a front elevation of the same.

Figure 6 is a detailed view of the supporting means for the pan.

Figure 7 is a detailed perspective view of the lifting rack, and

Figure 8 is a detailed perspective view of one of the pans.

50 Referring to the drawings by numerals, the apparatus comprises the cabinet 1, which includes a main frame formed of four upright channel members 2 at the corners of the cabinet and held in properly spaced relation by the top cross bars 3 and the base bars 4. Side and rear walls of the cabinet

are formed by the panels 5 and 6 and the front of the cabinet is provided with a transparent door 7 hingedly mounted and adapted to be swung open whereby access 60 may be had to the interior of the cabinet.

The corner posts 2 form guides for the movable pans 8 which are arranged in superposed relation within the cabinet and are relatively shallow to contain a quantity of 65 oats and water, whereby the oats are sprouted. Each pan 8 is provided at each corner with a standard 9 and these serve as support to engage in the adjacent upper pan 70 when all of the pans are lifted.

Swing shelves 10 are provided to support the pans in position, and, as shown to advantage in Figure 6, each shelf 10 comprises a spring band 11 having a supporting flange 12 to receive the pan, and an upturned lip 13, the terminals of which are extended to the channels in the posts 2 to limit the outward swinging movement of the shelves. The spring action of the spring band 11 is assisted by coil expansion springs 14 interposed between the bands 11 and the walls of the cabinet. In this manner the swing shelves are adapted to move outwardly when the pans are moved upwardly so that the pans may be elevated to a higher position 80 and, when lifting mechanism is released the pans will rest on the adjacent channels. The lowermost pan is supported upon a lifting rack 15 which comprises the side bars 16 and the rods 17, and this lifting rack is 90 attached to the lifting mechanism which is adapted to be operated by the foot of the operator. This lifting mechanism comprises a pressure bar 18 pivotally connected to the lower end of one of the corner posts, and also connected, near its pivoted end, with one end of the connecting link 19. The opposite end of the connecting link 19 is pivotally joined to the lower end of the lift lever 20 and the lift lever has its upper end attached to the lifting rack 15 making a 95 pivotal connection with one of the rack bars 16. The lift lever 20 is slightly curved as shown, so that it will assume the proper position for maintaining the lifting rack in 100 its upper position when the lifting mechanism is operated. An auxiliary link 21 is pivoted at one end to the base bar 4 of the main frame and has its opposite end connected by a pivot pin to the lift lever 20 to a 105 point on the latter near the lower end thereof. This arrangement of links and

levers is duplicated on the opposite side of the frame and the forward ends of the pressure bars 18 are attached to a foot rod 22 adapted to be engaged by the foot of the operator when the lifting mechanism is to be actuated.

The apparatus operates substantially as follows. The pans will be provided with a quantity of oats to be sprouted and they will be watered and moistened in the manner well known in the art. It is well known that in using devices of this character the best sprouted oats appear more quickly in the topmost pan. It is customary, therefore, to remove the uppermost pan and then raise the other pans one space and insert a new pan in the lowermost space. This requires considerable labor which is obviated by the present structure. The user removes the topmost pan from the cabinet, and he then has merely to place his foot on the foot rod 22 and exert a downward pressure thereon which will cause the pressure bars 18 to swing downwardly, thereby exerting a pull on the link 19, thus exerting an upward pressure on the lifting lever 20, which is controlled by the link 21 during its swinging movement so that the links and levers move from the positions shown in Figure 3 of the drawings to the positions shown in Figure 4 of the drawings, thus elevating the rack bar 15 to a higher position and permitting a pan to be inserted in the bottom of the frame after the lifting rack has been lowered. During the upward movement of the lifting rack 15, it engages the nearest pan and thrusts the same upwardly, and since the pans are arranged in superposed relation, the standard 9 will engage the adjacent pan and all of the pans will be lifted together and force the spring shelves inwardly to permit the pans to pass. After they have been elevated to the proper distance the spring shelves will spring outwardly and support the pans in their proper position as shown in Figure 3. The labor of removing all of the pans and replacing them, therefore, is entirely avoided.

Minor changes may be made in the details of construction without departing from the spirit of the invention or the scope of the claims hereunto appended.

What I claim is:

1. A device of the character described comprising a frame, a plurality of receptacles arranged in superposed relation in the frame, and engageable with each other, spring means to support each of said receptacles in spaced relation, and manually operating lifting means below the lowermost receptacle to be actuated for forcing said lowermost receptacle upwardly, whereby all of said receptacles will be simultaneously elevated.

2. In a device of the character described comprising a frame, a plurality of receptacles arranged in superposed relation in the frame, standards carried by each receptacle for engagement with the receptacle thereabove, spring means to support each of said receptacles in spaced relation, and manually operated lifting means mounted in the frame to exert an upward pressure against the lowermost receptacle which will cause the standards of each receptacle to engage the receptacle thereabove to elevate the same.

3. A device of the character described comprising a supporting frame, a plurality of receptacles arranged in superposed relation and engageable with each other, and adapted for vertical movement in the frame, a lifting rack disposed beneath the lowermost receptacle, a foot rod, pressure bars pivotally connected to the frame, a lift lever pivotally connected to the lifting rack, a connecting link joining one end of said lifting lever to the pressure bar, and an auxiliary link connecting said lifting lever to the frame.

In testimony whereof, I have affixed my signature in the presence of two witnesses.

CHARLES C. CLOUSER.
